UNITED STATES PATENT OFFICE.

THOMAS R. BRUMBACK, OF ST. JOSEPH, MISSOURI.

FASTENER FOR GRAIN-DOORS.

1,206,810.

Specification of Letters Patent.

Patented Dec. 5, 1916.

Application filed February 17, 1916. Serial No. 78,861.

To all whom it may concern:

Be it known that I, THOMAS R. BRUMBACK, a citizen of the United States, residing at St. Joseph, in the county of Buchanan and State of Missouri, have invented certain new and useful Improvements in Fasteners for Grain-Doors, of which the following is a specification, reference being had to the accompanying drawing.

10 My invention relates to improvements in fasteners for grain doors, the objects of which are, to provide a freight car door, in which all of the elements required for use in a grain door, such as a relief door and upper doors, shall be so combined and operated, that they can be simultaneously locked, and to provide locking devices whereby all of said doors, including the car door, are instantly locked.

15 Further objects are, to so construct said locking devices, that the same can be sealed by the use of one ordinary car door seal.

I attain the objects by the mechanism illustrated in the accompanying drawing, in which:—

Figure 1 is an outer side elevation of the car door and a portion of a car. Fig. 2 is a horizontal section on the line V V, seen in Fig. 1, looking downward. Fig. 3 is a horizontal section of the relief door, on the line W W, seen in Fig. 1, looking downward. Fig. 4 is an enlarged vertical section on the line X X, of the locking bolt in detail, seen in Fig. 6, looking toward the left. Fig. 5 is an enlarged horizontal section in detail, cut through the center of the outer end portion of the locking bolt, looking downward. Fig. 6 is a transverse section, on the line Y Y, seen in Fig. 1, looking toward the left. Fig. 7 is a side elevation of the inner side of the door and of a part of a car. Fig. 8 is an enlarged front elevation of the relief door lifting means, showing the parts released for lifting. Fig. 9 is a transverse section on the line Z Z, seen in Fig. 1, looking toward the left.

Referring to Fig. 6, car door 1 is slidably guided by rails 2 and 2', which are formed with plates 3 and 3', respectively. The top surface of plate 3 is set flush with the upper surface of floor 3'', while plate 3' is secured to the bottom surface of cap sill 4. Transporting wheels 5 rest on rail 2 and are rotatably mounted in said car door for trans-portably supporting the latter. Upper wheels 5' are similarly mounted in the upper

edge portion of said door for preventing lateral tilting or cramping of the corners of the door. Rack 6 is secured on the lower portion of said door, said rack having its outer surface flush with the outer surface of said door and being in engagement with pinion 7, secured on the inner end of shaft 7', which is rotatably mounted in hub 8', formed with ratchet plate 8, which latter is secured on the outer surface of the side 9, of an ordinary freight car. Said shaft is rotated by handle 10, secured on the outer end of said shaft; said handle being provided with latch 10', which is adapted to engage the teeth of said ratchet plate, for detachably holding said door 1 in closed position. Said latch is provided with latch handle 10'', for disengaging it from said engagement. Said parts are protected from mechanical injury and from the elements by ratchet shield 8'', seen best in Fig. 1.

Car door 1 has a grain opening 11' formed through its lower portion, which is controlled by relief door 11, which is mounted for vertical, slidable movement in said car door. The lower end of relief door rack 12 is secured on the upper surface of relief door 11; said rack being in engagement with pinion 13; said pinion having hubs 13' formed therewith, which are rotatably mounted in car door 1. Square socket 13'' is formed through the outer one of said hubs, and through said pinion, for forming a socket the inner end of which is closed. Said socket is adapted to receive the square end of any ordinary square shanked socket wrench, (not shown,) which may be formed in any suitable manner for rotating pinion 13. Upper doors 15 and 16 are slidably guided for horizontal movement in counter-sink 1' formed by a paneled portion of car door 1, seen in Fig. 7. Said countersunk panel has an upper opening 1'', formed therethrough, which is controlled primarily by said upper doors. Said opening is of such size as will readily permit passage therethrough of the person of a car in-spector, manually handled grain or other freight, and passage therethrough of a pneumatic grain tube, not shown. Door 16 has latch hook 17 pivotally connected with its inner edge portion; said hook being engaged with the adjacent edge portion of door 15. Said hook has seal strap slot formed through its free end portion, said slot being adapted to have the strap of an

ordinary car seal, (not shown,) passed therethrough. Door 16 is stopped at the limit of its inward movement, by stop 16'', indicated by dotted lines in Fig. 1. Said hook 17 is adapted to be rotated clockwise, through mortises 16' formed through doors 15 and 16, for releasing the doors.

Referring to Figs. 7 and 9, shield door 18 is slidably mounted for vertical movement, in the inner, upper portion of car door 1. Said shield door is frictionally held at any desired height, for preventing outflow of grain, when doors 15 and 16 are open.

Referring to Fig. 1, wooden boards 18' are secured on the paneled surfaces of doors 15 and 16, and on the side 9, of the car, for holding cards, (not shown,) tacked thereon, for carding the car in the usual manner.

Referring to Figs. 6 and 5, car door 1 is provided with lock bolt 19, which is actuated to move inward, by spring 20. Said spring and the outer portion of said bolt are housed in housing 21, which has weather shield 21' formed therewith seen in Fig. 1. Seal strap slot 21'' is formed through the outer end of said housing, while another seal strap slot 22, is formed through the outer end portion of bolt 19, in register with the slot 21'', for reception through both of said slots, of the strap of an ordinary car seal, not shown. The inner end of said bolt has sloped face 19' formed thereon, and has spline 19'' formed therewith, which is passed through aperture 21'', formed through the inner end of said housing, for holding said bolt against rotation. Sloped face 19' of bolt 19, is adapted to lift the free end of L crank 23, when said bolt is slid inward, and to allow said free end of said L crank to gravitate, when said bolt is manually moved outward. Said L crank is pivotally mounted in car door 1, and has its upper end pivotally connected with the right end of connecting rod 24, the intermediate portion of said rod being pivotally connected with the lower end of crank 26, which latter terminates at its lower end in forming the depending lock bar 25. The intermediate portion of crank 26 is pivotally mounted in car door 1, while its free end engages door 16, for locking said door in closed position. Door 15 is similarly locked by the free end of lock crank 27, which is L shaped and has its lower end pivotally connected with the left end of connecting rod 24. The lower end of lock bar 25 engages the upper portion 14' of one of the guides 14, for locking relief door 11 in closed position, and is adapted to be swung therefrom, to the position seen in Fig. 8, for unlocking said relief door.

Referring to Figs. 1 and 2, door 1 has channel 28 formed throughout the left edge thereof; said channel being engaged with tongued door casing 29, for forming a

weather and grain proof joint. Said car door has the double flanged strip 30, formed therewith, the inner edge of which engages the flanged edge of post 31, while the outer flanged edge of said strip engages the flanged edge of door casing 32, for forming grain proof and element proof joints respectively. Posts 31, 33 and 34 have the preferably sheet metal panel 35, secured thereon, and wooden car lining 36 secured thereon against said panel. The space between said panel and the side 9, of the car forms a door pocket 37, into which car door 1 is slid when opened. The right end of said pocket is closed by lining piece 38. Said pocket is provided with clean-out doors 39, and since said doors may be of any suitable kind for closing an opening, the same are neither fully shown nor fully described.

In operation, with the parts in the position seen in Figs. 1 and 6; the car door sealer passes the strap of an ordinary car door seal, (not shown,) through slots 21'' and 22, (see Fig. 5,) thereby sealing the hereinbefore described locking means. The thus sealed car is manually opened by the operator, who draws bolt 19 outward, (see Figs. 5 and 6,) which at the beginning of its movement, shear-cuts said seal strap, thus unsealing said car door. The operator continues to draw said bolt, (overcoming spring 20,) until spline 19'' has passed outward through the inner end of housing 21. He then rotates said bolt until said spline is out of register from spline slot 21'', (see Fig. 4,) and releases said bolt, which is thereby detachably held in its outward position. When said bolt is thus drawn, the free end of L crank 23 gravitates and rests on the bottom of slot 23'. This movement of said L crank, moves rod 24, (see Fig. 1,) toward the right, which movement is conveyed to the lower portions of lock cranks 26 and 27, thereby moving their free ends downward, from engagement with doors 15 and 16, unlocking said doors. This movement of crank 26, swings lock bar 25, from the position indicated in Fig. 1, to the position seen in Fig. 8, thus unlocking relief door 11. While the parts in the described position, any or all of the described doors may be independently opened, as desired. If the car be loaded with grain, ready for an inspector to take samples therefrom, said inspector unhooks hook 17, (see Fig. 1,) slides doors 15 and 16 from each other, and enters and leaves the car through the opening thus disclosed. If the car is to be emptied of grain, or of any other substance that will readily flow, such as gravel, nut coal and the like, the beforementioned socket wrench is inserted in socket 13'', and pinion 13 is thereby rotated clock-wise. This rotation lifts the therewith engaged rack 12, which lifts relief door 11, thereby permitting flow of grain.

said substance, through the lower opening through car door 1. After the pressure of said substance is thus removed from said car door, said operator removes said wrench, 5 after which said relief door gravitates to the position shown. Said operator then releases latch 10' from its ratchet engagement and rotates handle 10 clock-wise. This rotates pinion 7, which draws rack 6 and the 10 therewith connected door 1, toward the right, thus opening said car door. Shield door 18 is slid to such height as the height of grain or other substance may determine for preventing outflow of same, when said 15 upper doors are opened, as previously described, and is lowered to the limit of its downward movement, when freight is manually passed through opening 1", seen in Fig. 2. Should fine dust or other extra fine 20 sediment, accumulate on the bottom of door pocket 37, doors 39 are opened, and said dust is removed therethrough.

Having fully described my invention, what I claim as new and desire to secure by 25 Letters Patent, is:—

1. The combination with a freight car door having a plurality of smaller doors movably mounted therein and also having door holding means for detachably holding 30 said smaller doors in closed position; of a bolt housing secured on the outer side of said freight car adjacent to the rear edge of said car door said housing having seal strap slots formed through the outer end portion 35 thereof; a bolt slidably and rotatably mounted in said housing said bolt having another seal strap slot formed therethrough said other slot being adapted to be moved from and into register with the first mentioned 40 slots positioned therebetween; a spring in said housing whereby said bolt is moved inward projecting the inner end portion of said bolt behind said rear edge of said car door for locking the same in closed position; 45 bolt holding means whereby said bolt is detachably held in its outward position against the action of said spring said bolt holding means being released by rotation of said bolt; and moving means operated by the 50 inner end of said bolt whereby all of said door holding means are simultaneously moved into operative position when said

bolt is moved inward; the whole forming spring actuated sealable locking means whereby all of said doors are simultaneously 55 locked.

2. The combination with a freight car door having a plurality of smaller doors movably mounted therein and having door holding means therein for detachably holding 60 said smaller doors in closed position; of bolt mounting means secured on the outer side of said car adjacent to the rear edge of said car door; a bolt slidably mounted in said mounting means; a spring for actuating said bolt to move inward projecting the inner end portion of said bolt behind the rear edge of said car door; moving means actuated by the inner end portion of said bolt for moving all of said door holding 65 means into operative position when said bolt is moved inward said door holding means being adapted to be reversely moved by gravitation thereof when said bolt is moved outward; and car sealing means formed in 70 said bolt and said mounting means for the reception of the strap of an ordinary car seal.

3. The combination with a movably mounted freight car door; of a bolt housing 80 secured on the outer side of said freight car adjacent to the rear edge of said door said housing having a bifurcated outer end portion formed therewith and seal strap slots formed through said bifurcations said housing 85 also having an aperture formed through its inner end said aperture being adapted to loosely fit around a splined bolt; a lock bolt slidably and rotatably mounted in said housing; a spline formed on the inner end portion 90 of said bolt; a spring in said housing for at all times actuating said bolt to move inward said bolt having a seal strap slot formed through its outer end portion adapted to be brought into register with the first 95 mentioned slots by said movement; and shielding means for shielding said slots from the action of the elements.

In testimony whereof I affix my signature in the presence of two witnesses.

THOMAS R. BRUMBACK.
